UNITED STATES PATENT OFFICE.

DAVID J. NYSEWANDER, OF NEW CARLISLE, OHIO.

DOUBLE-ACTING FORCE-PUMP.

SPECIFICATION forming part of Letters Patent No. 326,053, dated September 8, 1885.

Application filed May 19, 1885. (No model.)

To all whom it may concern:

Be it known that I, DAVID J. NYSEWANDER, a citizen of the United States, and a resident of New Carlisle, in the county of Clark and State 5 of Ohio, have invented certain new and useful Improvements in Double-Acting Force-Pumps; and I do hereby declare that the following is a full, clear, and exact description of the invention, which will enable others 10 skilled in the art to which it appertains to make and use the same, reference being had to the accompanying drawings, which form a part of this specification.

My invention relates to that class of pumps 15 known as "double-acting force-pumps;" and it has for its objects greater simplicity of construction, combined with increased efficiency in operation, the inner pump-cylinder being further provided with an automatic device 20 which drains the water from the discharge-pipe to a point below the freezing-point without allowing any of the water to escape or waste.

To these ends my invention consists in the 25 improved construction and combination of parts of a pump of the above described class, which will be hereinafter fully described, and pointed out in the claims.

Referring to the annexed drawings, Figure 30 1 is a longitudinal vertical sectional view of my improved double-acting force-pump. Fig. 2 is a transverse sectional view taken on the plane indicated by line x x , Fig. 1, and Figs. 3 and 4 are detail views, respectively, of the 35 piston and the lifting-bucket.

The same letters of reference indicate corresponding parts in all the figures.

Referring to the several parts by letter, A represents the outer or main cylinder, which 40 is provided at its lower end with the end piece or cap, B, the central opening or inlet-port, B', of which is closed by the inwardly-opening valve b , the operation of which will be hereinafter described. The upper end of 45 the cylinder A is covered by the end piece or cap, C, having the central aperture at the point where the piston-rod I passes through the same, the cap C being further provided at one side of the said central aperture with the 50 screw-threaded recess c , for the reception of

the lower end of the pipe F', which forms a part of the air-chamber F, and has its upper end inserted in a similar screw-threaded recess, g , in the lower side of the base G of the pump-stock, the recess in the cap C connecting by a small vertical aperture, c' , with the air-chamber proper, which is formed by the space between the upper portion of the outer cylinder and the inner cylinder, H.

H represents the auxiliary inner cylinder, 55 which is secured at its upper end to the annular interior shoulder, c^3 , of the cap C, the said cylinder being of such a size that its capacity is equal to one-half of that of the outer cylinder, A, the main cylinder A being tapped at 60 about its center at a' , for connection with the lower end of the discharge-pipe A'.

I indicates the piston-rod, at the lower end of which is secured the lifting-bucket K, (shown in detail in Fig. 4 of the drawings,) 70 the said bucket consisting of the metallic bracket K', to the upper portion of which the lower end of the piston-rod is secured, the combined washer, plunger-packing, and valve K², consisting of a single disk of leather, the 75 center of which is cut around for nearly an entire circle, leaving sufficient connection with the washer proper to form a hinge, the valve thus formed being arranged to open upward as the bucket descends, and the metal ring or 80 annular plate K³, which is held in place by the screws K⁴, and, in conjunction with the metallic plate or ring, serves to hold the lifting-bucket in position, thus forming a solid 85 connection, and at the same time leaving a large clear passage for the water. The lower portion of the metal bracket K' is formed in the shape of a ring, the lower face of this metallic ring bearing against the upper face of the disk K², forming the combined washer, 90 plunger-packing, and valve, while its outer face or periphery is slightly beveled at k' , to adapt it to fit against the inner face of the annular upwardly-turned flange k^3 of the leather disk K², the said lower ring-shaped 95 portion of the metallic bracket thus serving not only for a means of attachment of the said disk to the bracket, but also serves to brace and hold in its operative position the annular upwardly-turned flange of the said disk, which 100

forms the plunger-packing and washer for the lifting-bucket, this arrangement obviating the necessity of employing an additional piece of metal for a bracing-ring for the said upwardly turned annular flange, which it would be necessary to employ if the lower portion of the metallic bracket were not constructed in this peculiar manner.

L indicates the upper piston, which works 10 within the inner cylinder, and which is secured upon the piston-rod at such a point that when the lifting-bucket is lowered to the bottom of the outer cylinder the said piston will be in close proximity to the bottom of the 15 inner cylinder, H. The piston L is composed of the following parts: A jam-nut, L', is secured upon the piston-rod I at a suitable point. Above this nut is placed a metal sleeve, L², upon the upper end of which bears a stationary disk, L³, having the vertical apertures l³, while above this disk is placed a leather washer, L⁴, and above this the nut L⁵, for securing the whole in place, both the nut L⁵ and washer L⁴ being provided with the vertical 20 apertures l⁵ and l⁶, which register with the vertical apertures l³ of the stationary disk L³. Upon the sleeve L² slides a movable disk, L⁶, of a sufficient diameter to cover the apertures of the stationary disk when elevated against 25 the lower side of the stationary disk L³.

The operation of my improved pump is as follows: The water enters the lower portion of the outer cylinder, A, (which in very deep wells may form a separate chamber and be 30 connected to its upper portion by a suitable connecting-pipe,) through the lower aperture or inlet-port B' of the same, opening the valve b as it enters. On the downstroke of the piston-rod the inlet-port B' is closed by the valve b, 35 and the water forces open the valve K² of the lifting-bucket and passes above the said bucket. On the upstroke of the piston-rod one half of the water in the lower portion of the outer cylinder enters the inner cylinder, 40 (the capacity of which, as before stated, is one-half of that of the outer cylinder,) while the other half of the body of water which has entered the outer cylinder passes up through the discharge-pipe under the action of the lifting-bucket. The pressure of the water as it enters the inner cylinder forces the movable disk L⁶ up against the lower face of the stationary disk L³, thereby closing the openings l⁵ l⁶ l³, and on the downstroke of the piston-rod 45 the lower portion of the outer cylinder is again filled, as before described, while the piston L operates to force the water from the inner cylinder up through the discharge-pipe, thus causing a continuous flow of water from the 50 spout.

The air-chamber proper, F, which is formed by the space between the upper part of the outer cylinder and the inner cylinder, extends 55 completely around the walls or sides of the cylinder, as clearly shown in Fig. 2 of the drawings, so that as the water passes upward

it comes in direct contact with the air-cushion above, and is thus discharged without any of the jar or jerk which occurs when the air-chamber is located to one side alone of the cylinder, the circular air-chamber which surrounds the inner cylinder being entirely closed at its top, so as to preserve intact the circular air-cushion formed by the air surrounding the inner upper cylinder, this arrangement causing the air-cushion to act more smoothly, evenly, and effectively than would be the case if the air-chamber surrounding the inner upper cylinder were so constructed as to admit of the water passing up through the said chamber at 80 certain points, as it is forced up to the discharge-spout under the pressure of the pistons, as has heretofore been the case.

While the pump is in operation the disk L⁶ is forced up against the stationary disk L³, thereby closing the apertures l⁵ l⁶ l³, as before described, thus letting no water escape; but when the pump is not in operation the movable disk L⁶ falls by its own weight away from the lower face of the perforated disk L³ 90 down upon the jam-nut L', and the water-passage through the piston L is thus left open. The water standing in the upper portion of the discharge-pipe will then, seeking its level, run down into the outer cylinder, the lower portion of which is filled by the water rising through the opening B', and the water in the lower portion of the outer cylinder thus rising will enter the inner cylinder, H, through the open lower end thereof, and will rise through 100 the perforations of the upper piston, L, and pass above the same in the inner cylinder, the water being thus removed to a point below the freezing-point, while at the same time no waste of water is allowed while the pump 105 is in operation, thus forming an automatic anti-freezing device.

From the foregoing description, taken in connection with the accompanying drawings, the construction and operation of my improved double-acting force-pump will be readily understood without requiring further explanation.

It will be seen that my improved pump is simple in construction, and therefore inexpensive to manufacture and not liable to break or get out of order, while at the same time it is very efficient in its operation. The peculiar construction of the upper piston effectually prevents the freezing of the water in the 120 pump.

Having thus described my invention, what I claim, and desire to secure by Letters Patent of the United States, is—

The combination, with the outer and inner 125 cylinders and the discharge-pipe, of the piston-rod having the lifting-bucket composed of the metal bracket having the annular lower portion formed integral therewith and adapted to brace and hold in its operative position the upwardly-extending flange of the leather disk, the combined washer, plunger-packing,

and valve formed of a single piece or disk of leather, and the metal ring and binding-screws, and further provided with the automatic piston arranged to work in the inner cylinder, and consisting of the stationary disk, the washer, and the upper binding-nut, provided with the registering-apertures, and the movable disk adapted to slide upon the vertical sleeve and prevented from falling too low by the jam-nut, substantially as set forth.

In testimony that I claim the foregoing as my own I have hereunto affixed my signature in presence of two witnesses.

DAVID J. NYSEWANDER.
